UNITED STATES PATENT OFFICE.

STANLEY G. JOHNSON, OF DETROIT, MICHIGAN, ASSIGNOR TO THE BURKHARDT COMPANY, OF DETROIT, MICHIGAN, A CORPORATION OF MICHIGAN.

DISPLAY BOOK.

Application filed December 13, 1926. Serial No. 154,601.

This invention relates to loose-leaf binders adapted to be utilized as easels for display purposes and so constructed that the front and back of the binder cover may be maintained in inverted V relation when operating 5 as an easel.

The object of the invention is to provide a very simple means of maintaining a fly-leaf in a raised position so that it forms to 10 all intents and purposes a V extension of the member of the cover forming the front of the easel and permits the display of leaves of the binder in open form, so that two leaves may be simultaneously exposed or so 15 that the leaves may be successively turned to an upward position for the successive exposing of the underlying leaf or vice versa such as may be required in the case of a 20 stenographer's note book, the invention also contemplating the use of the fly-leaf in such relation to the members of the cover that when the device is operating as an easel the members of the cover forming the front of the easel are held in more or less rigid 25 alinement and actuate to maintain the said fly-leaf in a fixed raised position.

Further objects subsidiary to or resulting 30 from the aforesaid objects or from the construction or operation of the invention as it may be carried into effect, will become apparent as the said invention is hereinafter further disclosed.

In carrying the invention into effect, I 35 may provide a loose-leaf binder with a reversible cover comprising front and back boards connected together by an intermediate member spacing said boards to provide accommodation for a binder mechanism secured to one of said boards proximate to said 40 intermediate member, as distinguished from its being secured actually to the intermediate member as is the common practice in loose-leaf binder construction, means being provided for relatively positioning the ends 45 of said boards when reversed for use in easel formation, and a fly-leaf carried by the binder mechanism, said fly-leaf being provided with fasteners for its attachment in a raised position to the cover or member of 50 the binder entering into the formation of the front of the easel which is arranged for that purpose, so that such connection of the fly-leaf to the binder locks the said fly-leaf in such raised position and braces the intermediate portion and the board of the binder 55

forming the front of the easel in a more or less rigid alinement or relationship.

All of which is more particularly described and ascertained hereinafter, by way of example, having reference to the accompanying drawings, wherein—

Figure 1 is a perspective view of a loose-leaf binder easel embodying the said invention;

Figure 2 is a side elevation of the device 65 closed;

Figure 3 is a detail fragmentary sectional side elevation illustrating the principal features of the invention;

Figure 4 is a similar view to Figure 1 70 illustrating a modified form of the invention;

Figure 5 is a similar view to Figure 2 of such modified form; and

Figure 6 is a similar view to Figure 3 75 of the said modified form.

Similar characters of reference indicate similar parts in the several figures of the drawings.

1 and 2 are front and back boards of the binder cover hinged at 3 and 4 to an intermediate member 5 forming a spacer for the said boards to provide room therebetween for the binder mechanism and leaves carried thereby, 6 being the binder mechanism including rings 7 from which leaves 8 are suspended in a manner well known in the use 80 of loose-leaf binders.

9 is a fly-leaf also carried by the rings 7 of the binder mechanism, the purpose of 90 which fly-leaf will be hereinafter more fully explained, and 10 is an extension of the board 2 of the binder cover being flexibly hinged thereto at 11 and having a hingedly attached flap 12 at its extremity.

Contrary to the general practice the binder mechanism 6 is carried by the board 2 of the binder cover instead of by the intermediate member 5 and at a short distance from the said intermediate member for reasons which 100 will become duly apparent.

The cover of the binder is adapted to be formed into an easel by inversely flexing the board 1 on the hinge 3 to form the back of the easel whereby the board 2 and member 5 form the front of the easel and the extension 10 forms the base, the flap 12 of which is provided with studs 13 adapted to be engaged by snap fasteners 14 carried by the end portion of the said board 1.

The particular arrangement of the extension 10 as a means of securing the board 1 in position as the back of the easel is not especially important so far as this invention is concerned, as any suitable means may be employed for that purpose and the essence of the invention lies in a general arrangement shown in detail in one of its forms in Figure 3.

- 10 Referring to Figures 1, 2 and 3 more particularly, the fly-leaf 9 is indicated as having its inner end disposed towards the binder mechanism divided into two tongues 9^a and 9^b, the first of which is flexibly connected at 9^c to the body of the fly-leaf and is engaged by the rings 7 of the binder mechanism and the other tongue 9^b is of a substantially rigid extension of the fly-leaf.
- 15 15 are fasteners carried by the said fly-leaf adjacent the junction of the said tongues thereof and adapted when the fly-leaf is raised to the position in Figures 1, 2 and 3, to be engaged with studs 16 on one of the members forming the front of the easel, this being in the example illustrated in Figures 1, 2 and 3, the board 2 of the binder cover.

20 The tongue 9^b of the fly-leaf 9 is so proportioned that upon the engagement of the fasteners 15 of the studs 16 it may be held in engagement with the back of the binder mechanism 6 as clearly illustrated in Figure 3, that is, it is held in the position in which the edges of the said tongues 9^b are maintained and the angle formed between the said binder mechanism and the board 2 on which the binder mechanism is mounted. This forms a brace for the fly-leaf when in its raised or display position, so that it is well able to withstand the weight of a number of leaves or display cards which may be supported thereby, and the fly-leaf resting on the member 5 and being secured to the studs 16 of the member 2 resists the tendency of the hinge 4 to give way under the weight of the binder mechanism and leaves carried thereby, so that the said members 2 and 5 are maintained in proximate alignment to a sufficient extent to adequately perform their supporting functions.

- 25 50 In the modified arrangement shown in Figures 4, 5 and 6, a simple fly-leaf 17 is

shown in which the tongue 17^a is practically rigid therewith and is engaged by the rings 7 of the binder mechanism, the said tongue 17^a forming a more or less rigid link 35 between the studs 19, in this case carried by the member 5 and the rings of the binder mechanism, 15 being the snap fasteners on the fly-leaf 17 for engagement with the said studs 19. This practically rigid connection between said studs 19 and the rings of the binder holds the member 5 against undue flexion with respect to the member 2 when the said fly-leaf is in its raised or display position, so that the members 5 and 2 are 65 adequately supported against relative flexion by the said fly-leaf, and the fly-leaf is effectively maintained in its raised display position, so that the use of braces of any character behind the fly-leaf to effect its 70 support is rendered unnecessary.

This invention may be developed within the scope of the following claims without departing from the essential features of the said invention, and it is desired that the 75 specification and drawing be read as merely illustrative and not in a limiting sense, except as necessitated by the prior art.

What I claim is:—

1. In a loose-leaf binder, a reversible cover 80 comprising front and back boards, binder mechanism secured to one of said boards, a fly-leaf swingably mounted on said binder mechanism, and a tongue on said fly-leaf adapted to engage behind the binder mechanism when the fly-leaf is in its raised position.

2. In a loose-leaf binder, a reversible cover comprising front and back boards and an intermediate connecting member, binder 85 mechanism secured to one of said boards proximate to said intermediate member, means relatively positioning said boards when reversed for use in easel formation, a fly-leaf swingably mounted on said binder 95 mechanism, and a tongue on said fly-leaf adapted to engage behind the binder mechanism when the fly-leaf is in its raised position.

In testimony whereof I affix my signature.

STANLEY G. JOHNSON.
